UNITED STATES PATENT OFFICE.

EDWARD T. WILLIAMS, OF BROOKLYN, NEW YORK.

HOUSEHOLD REFRIGERATING APPARATUS.

Application filed February 17, 1923. Serial No. 619,601.

To all whom it may concern:

Be it known that I, EDWARD T. WILLIAMS, a citizen of the United States of America, residing at Brooklyn, county of Kings, city 5 and State of New York, have invented certain new and useful Improvements in Household Refrigerating Apparatus, of which the following is a full, clear, and exact description.

10 This invention relates to refrigerating apparatus, more particularly devices designed for household use, and its chief object is to provide for the purpose an apparatus of simple construction and low cost which can 15 be operated with high efficiency. To this and other ends the invention consists in the novel features hereinafter described.

In carrying out the invention in the preferred manner I employ a "refrigerator," 20 which may be of any suitable type, with the usual heat-insulating-walls. Inside of the refrigerator, preferably in a rear corner thereof, I provide an upright elongated flue, open at top and bottom and also having 25 heat-insulating walls, in which is an upright elongated brine tank spaced from the inner surface of the flue to provide air passages. The brine tank surrounds a long narrow upright expansion chamber, to which 30 liquefied refrigerant is supplied from a refrigerating machine located outside of the refrigerator, preferably on top of the same. In the lower end of the brine tank one or 35 more freezing chambers may be provided, in which ice for table use and the like may be made in convenient quantities.

The embodiment outlined above is illustrated in the accompanying drawings, in which,

40 Fig. 1 is a cross sectional view of a refrigerator equipped with my invention, the section being taken on a plane corresponding to the line 1—1 in Fig. 2;

45 Fig. 2 is a detail sectional plan view on line 2—2 of Fig. 1;

Fig. 3 is a detail section on line 3—3 of Fig. 2, looking in the direction of the arrows; and

50 Fig. 4 is a detail sectional plan view on line 4—4 of Fig. 3.

The refrigerator shown is of any suitable construction, having heat-insulating walls, and in its left rear corner a space is partitioned off by heat-insulating walls 10, 11, 55 which, in conjunction with the refrigerator

walls 12, 13, Fig. 2, form an upright, relatively long narrow flue, open at top and bottom and spaced from the top and bottom of the refrigerator, as clearly shown in Fig. 1. The walls or partitions 10, 11, may be of any 60 suitable construction. Preferably the flue is substantially square in horizontal section.

In the flue is an upright brine tank 14 of elongated form, somewhat smaller than the flue in horizontal dimensions so as to leave 65 ample space between the tank and the flue walls for circulation of air, as indicated by the arrows in Fig. 1. Preferably the major portion of the brine tank is made of a piece 70 of round iron or steel pipe, say about six inches in diameter. At the bottom, below the flue, the tank is enlarged by an extension 75 15, rectangular in horizontal section, which may be welded or otherwise secured to the pipe.

Extending into the brine tank from above, so as to be well immersed in the brine therein, is an elongated cylindrical expansion chamber 16, which may also be made of a piece of iron or steel pipe, say about 2½ 80 inches in diameter, with its ends closed in any convenient manner, as by means of caps 17, 18, threaded or welded on. The flue, brine tank, and expansion chamber are preferably concentric with each other, as indicated in Fig. 2.

A refrigerating machine on top of the refrigerator is indicated diagrammatically in Fig. 1 by the housing 19, containing a condenser 20, a compressor 21, and an electric 90 motor 22 to drive the latter. Liquefied refrigerant (preferably ethyl chlorid) is delivered from the refrigerating machine to the expansion chamber by a pipe 23, and evaporated refrigerant is conveyed to the compressor by a pipe 24 leading from a trap 24a. When the machine is not in operation, lubricant (glycerine) running down the suction pipe 24 is caught in this trap and is immediately drawn back to the compressor when 100 the machine is started again.

The expansion chamber may be supported by the brine tank cover 25, Fig. 3, and the brine tank itself may be mounted on a standard 26, Fig. 1. To steady the whole the expansion chamber is extended up into the top of the refrigerator. The standard 26, just mentioned, may be hollow, terminating below the refrigerator in a water seal 27 to 105 serve as a drain for moisture condensed on 110

and dripping from the brine tank. The water seal prevents escape of cold air from the refrigerator, as will be readily understood.

When the expansion chamber 16 is supplied with liquefied refrigerant the latter absorbs heat from the brine in the tank and is evaporated thereby, thus lowering the temperature of the brine, and causing the air to flow down through the flue and up outside of the same, as indicated by the arrows in Fig. 1, this circulation serving to carry heat from the contents of the refrigerator to the brine which in turn transmits the heat to the liquefied refrigerant in the expansion chamber. From the latter the refrigerant vapor, carrying the heat absorbed from the brine, passes to the compressor 21, where it is compressed, flowing thence to the condenser 20, where it is cooled to liquefaction for re-delivery to the expansion chamber. In this way the brine may be maintained at a temperature considerably below the freezing point of fresh water.

In the brine tank enlargement 15 I provide one or more freezing chambers. Two such chambers are shown, in the form of open ended sheet metal tubes or tunnels 28, 29, Figs. 3 and 4, extending through the brine tank horizontally from front to rear and welded or otherwise secured to the walls of the tank. Freezing pans or trays 30 are provided for the freezing chambers. When the pans are in place the water contained therein is surrounded by the more than ice-cold brine and is soon frozen, thus providing ice for table use and other purposes. The freezing pans may be divided into compartments by partitions 32, so that the ice will be frozen in block form. To prevent air circulation through the freezing chambers the rear ends thereof may be closed by plates 33 and the freezing pans may be equipped with covers 34 to close the front ends of the chambers.

It is to be understood that the invention is not limited to the specific details of construction herein illustrated and described, since these can be varied without departing from the spirit of the invention as defined by the appended claims.

I claim—

1. In a refrigerating apparatus, a refrigerator having side and rear walls, vertical partition walls associated with the side and rear walls of the refrigerator and forming in conjunction therewith a narrow elongated upright flue open at top and bottom, an elongated vertical brine tank arranged in said flue and spaced from the walls thereof to permit downflow of air therethrough, a cover for the brine tank, a tubular drain extending through the bottom of the refrigerator and supporting the brine tank, and

an elongated expansion chamber extending 65 into the brine tank through the cover thereof and supported by the latter.

2. In a refrigerating apparatus, in combination, a refrigerator, upright flue-walls therein defining a vertical flue open at both ends and spaced from the top and bottom of the refrigerator, an elongated brine tank arranged in the flue and spaced from the walls thereof to permit flow of air through the flue around the brine tank, an expansion chamber for liquefied refrigerant in the brine tank, and a freezing chamber in the brine tank at the bottom thereof below the flue.

3. In a refrigerating apparatus, in combination, a refrigerator having vertical walls defining a vertical elongated flue open at top and bottom, an elongated brine tank located in the flue and spaced from the walls thereof and extending below the flue, a freezing chamber extending rearwardly 80 into the portion of the brine tank below the flue for immersion in the brine in the tank, and an expansion chamber for liquefied refrigerant in the brine tank.

4. In a refrigerating apparatus, in combination, a refrigerator having walls defining an upright flue open at top and bottom, an elongated cylindrical brine tank arranged in the flue, spaced from the walls thereof for downflow of air around the brine tank and having an enlargement below the flue, a freezing chamber extending horizontally into the brine tank enlargement below the flue, and an elongated cylindrical expansion chamber for liquefied refrigerant in the brine tank.

5. In a refrigerating apparatus, in combination, a refrigerator having vertical inner walls spaced from the top and bottom of the refrigerator to form a vertical flue 95 open at both ends, a cylindrical brine tank of elongated form in the flue, spaced from the flue walls and extending below the bottom thereof, an elongated cylindrical expansion chamber for liquefied refrigerant in the brine tank, a freezing chamber of tubular form extending rearwardly into the brine tank below the flue, and a water-tray 105 slidable in the tubular freezing chamber.

6. In a refrigerating apparatus, in combination, a refrigerator having inner vertical walls forming a flue open at top and bottom, an elongated brine tank arranged in the flue and leaving an air space therein for downflow of air around the tank, an 110 elongated expansion chamber for liquefied refrigerant extending downwardly into the brine tank, and a freezing chamber in the brine tank below the expansion chamber and below the flue.

In testimony whereof I hereto affix my signature.

EDWARD T. WILLIAMS.
